(57) **CLAIM**

The ornamental design for a lamp as shown and described.

DESCRIPTION

FIG. 1 is a perspective view of a lamp body of a lamp, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof.

FIG. 9 is a perspective view of a tube of the lamp, shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the tube where the tube is in a first configuration of use;

FIG. 18 is a perspective view of the lamp shown in a first configuration of use with environmental cell phone;

FIG. 19 is a perspective view of the lamp shown in a second configuration of use;

FIG. 20 is a perspective view of the lamp shown in a third configuration of use; and,

FIG. 21 is a perspective view of the tube where the tube is in a second configuration of use with environmental computer.

The broken lines in the drawings depict portions of the lamp that form no part of the claimed design. The broken line showing of the cell phone in FIG. 18 and the computer in FIG. 21 depict environmental structures that form no part of the claimed design.

1 Claim, 21 Drawing Sheets
